(57) **CLAIM**

The ornamental design of a chafer griddle, as shown and described.

DESCRIPTION

FIG. 1 shows a perspective view of a chafer griddle showing a first embodiment of our design;

FIG. 2 shows a front elevation view of the chafer griddle of FIG. 1;

FIG. 3 shows a right side elevation view of the chafer griddle of FIG. 1;

FIG. 4 shows a rear elevation view of the chafer griddle of FIG. 1;

FIG. 5 shows a left side elevation view of the chafer griddle of FIG. 1;

FIG. 6 shows a top plan view of the chafer griddle of FIG. 1;

FIG. 7 shows a bottom plan view of the chafer griddle of FIG. 1;

FIG. 8 shows a perspective view of a chafer griddle showing a second embodiment of our design;

FIG. 9 shows a front elevation view of the chafer griddle of FIG. 8;

FIG. 10 shows a right side elevation view of the chafer griddle of FIG. 8;

FIG. 11 shows a rear elevation of the chafer griddle of FIG. 8;

FIG. 12 shows a left side elevation view of the chafer griddle of FIG. 8;

FIG. 13 shows a top plan view of the chafer griddle of FIG. 8; and,

FIG. 14 shows a bottom plan view of the chafer griddle of FIG. 8.

The broken lines are included for the purpose of illustrating portions of the chafer griddle that form no part of the claimed design.
